PER ARVID PETERSON, OF TRENTON, NEW JERSEY, ASSIGNOR TO DE LAVAL STEAM TURBINE COMPANY, OF TRENTON, NEW JERSEY, A CORPORATION OF NEW JERSEY.

CENTRIFUGAL PUMP.

1,308,108.

Specification of Letters Patent.

Patented July 1, 1919.

Application filed September 20, 1916. Serial No. 121,099.

To all whom it may concern:

Be it known that I, PER ARVID PETERSON, a subject of the King of Sweden, and a resident of Trenton, county of Mercer, and 5 State of New Jersey, have invented certain new and useful Improvements in Centrifugal Pumps, of which the following is a specification.

My invention relates to improvements in 10 centrifugal pumps, and particularly, to an improved arrangement of a baffle or baffles designed to cause the delivery of incoming fluid to the rotary impeller, without whirling of the fluid at the entrance to the impeller and without the formation of objectionable eddies and other disturbances. 15 My invention comprises a construction wherein a baffle or baffles is or are located in the inlet passage of the pump and is or 20 are supported on a bushing commonly provided around the impeller shaft.

The object of my invention is to improve the efficiency of centrifugal pumps and the like; and, as a means for doing so, to support in an improved manner one or more baffles in the inlet passage of the pump adjacent the point of entry of the fluid to the pump impeller.

I will now proceed to describe my invention with reference to the accompanying drawings, and will then point out the novel features in claims. In said drawings:

Figure 1 shows a fragmentary elevation and partial vertical section of a portion of 35 a double suction centrifugal pump embodying my invention.

Fig. 2 shows a transverse section through the water supply passage of the pump, and shows a baffle mounted on the before-mentioned bushing; and

Fig. 3 is a view similar to Fig. 2, except that two such baffles are shown mounted upon such bushings.

In the drawings, 1 designates an upper 45 section and 2 a lower section of the pump case, 3 the pump impeller, 4 the inlet to that pump impeller, 5 the fluid supply passage of the pump case, 6 the impeller shaft, 7 a bearing sleeve surrounding the impeller 50 shaft and 8 a further sleeve or bushing surrounding the bearing sleeve 7, and forming an abutment for the shaft packing 9. As indicated particularly in Fig. 1, this bushing is provided with a shoulder 10 seated in a 55 corresponding recess in one section of the

case, whereby said bushing 8 is held against longitudinal motion.

It has been found by experiment that the efficiency of centrifugal pumps may be increased considerably by the provision of a 60 suitable baffle plate at the top of the suction chamber or fluid entrance to the impeller. Such a baffle plate prevents the whirling of the water at the entrance of the impeller, and prevents objectionable eddies and 65 disturbances. Various attempts have been made to employ such baffle plates effectively, but difficulty has been found heretofore in providing a suitable support for such baffle plates. In some cases the baffle plate has 70 been riveted to the top part of the case, but this method of securing the baffle plate in place is expensive and in various ways is undesirable.

It is common practice in pumps to provide 75 a sleeve or bushing, such as the sleeve 8, extending in through the said suction chamber 5 of the pump. According to my invention I employ this sleeve or bushing 8 for the support of the baffle or baffles, such 80 baffle or baffles being, preferably, cast integrally or otherwise formed integrally with the bushing. In Figs. 1 and 2, 11 designates such a baffle so formed integrally with the bushing 8. As shown, it is at the top of 85 the suction chamber, and conforms generally to the cross section of that suction chamber at the point where such baffle is located, with suitable clearance, however, between the edges of the baffle and the walls 90 of the suction chamber. As will be clearly evident, such a baffle tends efficiently to prevent whirling of the fluid in the suction chamber, and to cause such fluid to enter the pump impeller in a substantially 95 axial direction, without loss of energy in eddies or other disturbances.

In some cases, as indicated in Fig. 2, a single baffle only is used. In other cases, as indicated in Fig. 3, an additional baffle, 100 12, may be provided, this baffle 12 being likewise formed integrally, preferably, with the bushing 8. In such case, the second baffle, 12, should preferably be formed to correspond with the axis of the flow passage 5 in which it is located. According to the design of the pumps, the curvature of such flow passages 5 differs greatly, and therefore in different designs of pump the curvature of the baffle 12 will differ cor- 105 110

respondingly; it being best as a rule that the curvature of such baffle 12 shall cause it to correspond substantially to the central axis of the portion of the passage in which 5 it is located.

What I claim is: —

1. In a centrifugal pump, the combination with a pump case having a suction chamber, and an impeller within that case having 10 an inlet in a plane transverse to the plane of rotation, to which inlet said suction chamber leads, of a shaft for such impeller, and a bushing surrounding such shaft and provided with a baffle located in such suction 15 chamber and arranged to reduce whirling of the fluid passing through such chamber on its way to the impeller.

2. In a centrifugal pump, the combination with a pump case having a suction 20 chamber, and an impeller within that case having an inlet in a plane transverse to the plane of rotation, to which inlet said suction chamber leads, of a shaft for such impeller, and a bushing surrounding such shaft

and secured against longitudinal motion and 25 provided with a baffle located in such suction chamber and arranged to reduce whirling of the fluid passing through such chamber on its way to the impeller.

3. In a centrifugal pump, the combination 30 with a pump case having a suction chamber, and an impeller within that case having an inlet in a plane transverse to the plane of rotation, to which inlet said suction chamber leads, of a shaft for such impeller, 35 and a bushing surrounding such shaft and provided with an integral baffle blade projecting from such bushing in a substantially axial plane into such suction chamber to near the top of such chamber. 40

In testimony whereof I have signed this specification in the presence of two subscribing witnesses.

PER ARVID PETERSON.
